ABSTRACT: A panty girdle forming a woman's undergarment. The girdle has an upper body-encircling portion and a pair of leg-encircling portions extending from and forming a continuation of the upper body-encircling portion. These leg-encircling portions have inner wall regions located adjacent and directed toward each other. These inner wall regions of the leg-encircling portions have a seam-free construction so that the girdle has a perfectly smooth construction at the crotch thereof.

PANTY GIRDLE

BACKGROUND OF THE INVENTION

The present invention relates to girdles.

In particular, the present invention relates to panty girdles which, as is well known, are provided with a crotch forming from the girdle a pair of relatively short leg-encircling portions.

With conventional girdles of this type, the crotch region is unavoidable provided with seams where fabric portions are joined to each other. For example, the crotch may be formed from individual panels which are joined to the remainder of the girdle by suitable seams.

This conventional construction is extremely uncomfortable because the fabric of the girdle is generally elastic and necessarily presses against the flesh of the wearer. The presence of the seams under these conditions creates considerable discomfort by rubbing against the skin, particularly during walking. Furthermore, the construction of the girdle is rendered fairly complex and expensive by reason of the inclusion of a crotch region to form the panty girdle.

SUMMARY OF THE INVENTION

It is accordingly a primary object of the present invention to provide a panty girdle which will avoid these drawbacks.

In particular, it is an object of the present invention to provide a girdle of relatively simple construction, which is less costly than conventional girdles, and which at the same time is more comfortable.

Thus, it is an object of the present invention to provide a panty girdle which will create no discomfort during wearing thereof and which will not undesirably chafe the skin of the wearer.

In accordance with the invention the panty girdle includes an upper body-encircling portion and a pair of leg-encircling portions which extend from and form a continuation of the upper body-encircling portion. These leg-encircling portions respectively have inner wall regions located adjacent and directed toward each other to form a crotch for the panty girdle, and these wall regions are free of seams, so that the panty girdle has a seam-free crotch which will not create any discomfort during wearing of the girdle.

BRIEF DESCRIPTION OF DRAWINGS

The invention is illustrated by way of example in the accompanying drawings which form part of this application and in which:

FIG. 1 is a front elevation of a panty girdle of the invention; FIG. 2 is a rear elevation of the girdle of FIG. 1; and FIG. 3 is a sectional plan view taken along line 3-3 of FIG. 1 in the direction of the arrows.

DESCRIPTION OF A PREFERRED EMBODIMENT

Referring now to the drawings, the panty girdle 10 of the invention includes an upper body-encircling portion 12 made of a stretchable elastic fabric, as is well known. The encircling portion 12 may be provided along its upper edge with an elastic band 14 to be situated at the waist of the wearer and provided with any suitable stays, as is conventional.

The girdle 10 includes a pair of leg-encircling portions 16a and 16b which extend from and form continuations of the upper body-encircling portion 12. These leg-encircling portions 16a and 16b are of relatively short length, as is conventional, and any suitable garters or the like may be connected with the girdle in a well-known manner.

The fabric sheet material of the girdle may have reinforcing sheet material attached thereto, and such reinforcing may take the form of a rear reinforcing insert 18, and a front reinforcing insert 20 as well as side inserts 22a and 22b. These inserts are simply in the form of sheets of fabric stitched to the

inner surface of the exterior layer of fabric, the stitching being indicated by the dotted lines 24.

The leg-encircling portions 16a and 16b are respectively formed from continuous uninterrupted webs of elastic fabric having seams 26a and 26b situated only and exclusively at outer sidewall regions of the leg-encircling portions 16a and 16b. The free edges of the leg-encircling portions 16a and 16b are not only bent over to form the seams 26a and 26b, but in addition they serve to connect to the inner surface of the exterior fabric part of the reinforcing inserts 22a and 22b in the manner shown in FIG. 3. These reinforcing inserts 22a and 22b and seams 26a and 26b are located only and exclusively at the outer wall regions of the leg-encircling portions, these outer wall regions being directed away from each other.

As a result, with this construction of the invention the leg-encircling portions 16a and 16b respectively have inner wall regions 28a and 28b which are completely devoid of any seams and which form uninterrupted sections of the elastic webbing which forms the leg-encircling portions 16a and 16b. Thus, the inner wall regions 28a and 28b which are located adjacent and directed toward each other form the crotch 30 of the girdle 10. This crotch 30 is of a completely seam-free construction so that it only has smooth continuous webbing engaging the wearer so as to avoid any possibility of chafing or other discomfort.

The girdle is completed by lace trimming 32 or the like located at the bottom ends of the leg-encircling portions 16a and 16b.

It is to be noted that because of the seam-free crotch 30 of the girdle of the invention not only is the comfort of the garment greatly increased and the possibility of chafing greatly decreased, but in addition the entire construction is simplified since the stitching required for seams is located only and exclusively at the outer wall regions of the leg-encircling portions, so that the cost of manufacture of the girdle is reduced as compared to conventional girdles.

The upper areas of the wall regions 28a and 28b may be joined together to form a closed crotch or may be separated to form an open crotch.

It is to be noted that all of the reinforcing inserts are situated at parts of the girdle 10 which are distant from the wall regions 28a and 28b of the leg-encircling portions 16a and 16b, so that in this way the comfort and chafe-free wearing of the garment, particularly at the inner leg regions is assured.

I claim:

1. A panty girdle comprising an upper tubular, body-encircling portion and a pair of lower leg-encircling portions extending from and forming a continuation of said upper portion and respectively having inner wall regions situated adjacent and directed toward each other and defining a crotch for the girdle, said wall regions being smooth and free of any seams, so that the girdle has a crotch of seam-free construction at the leg-encircling portions, and said leg-encircling portions respectively having seams situated only at wall regions of said leg-encircling portions which are distant from said inner wall regions.

2. The combination of claim 1 and wherein said seams of said leg-encircling portions respectively are side seams situated only at outer wall regions of said leg-encircling portions opposed to said inner wall regions thereof.

3. The combination of claim 2 and wherein said leg-encircling portions are respectively constructed of uninterrupted webbing having seams situated only at the region of said outer side seams at said outer wall regions.

4. The combination of claim 3 and wherein said upper body-encircling portion and leg-encircling portions are all made of an elastic fabric webbing.

5. The combination of claim 4 and wherein reinforcing inserts are connected with said upper body-encircling portion and in part overlap said leg-encircling portions while being located exclusively at the outer wall regions thereof.
